UNITED STATES PATENT OFFICE

124,045

DESIGN FOR A MINIATURE BASEBALL GAME BOARD

Guy O. Rupe, Hillsboro, Ill.

Application August 16, 1939, Serial No. 86,740

Term of patent 14 years

To all whom it may concern:

Be it known that I, Guy O. Rupe, a citizen of the United States, residing at Hillsboro, in the State of Illinois, have invented a new, original, and ornamental Design for Miniature Baseball Game Boards, of which the following is a specification, reference being had to the accompanying drawing, forming part thereof.

The figure is a plan view of a baseball game board, showing my new design.

The article is of no appreciable or substantial thickness.

I claim:

The ornamental design for a miniature baseball game board, as shown and described.

GUY O. RUPE.
